Inventor.

Clifford G. King

By Kenneth E. Billow

Attorney.

UNITED STATES PATENT OFFICE.

CLIFFORD G. KING, OF PROVIDENCE, RHODE ISLAND.

METHOD OF FORMING THE ORNAMENTAL BODY OF AN EAR-RING.

1,324,827.

Specification of Letters Patent.

Patented Dec. 16, 1919.

Application filed July 17, 1919. Serial No. 311,545.

To all whom it may concern:

Be it known that I, CLIFFORD G. KING, a citizen of the United States, residing at Providence, in the county of Providence and State of Rhode Island, have invented certain new and useful Improvements in Methods of Forming the Ornamental Body of an Ear-Ring, of which the following is a specification.

10 My invention relates to earring bodies of crescent form.

These bodies are usually made from flat precious metal plated material, in which case it is obviously essential that the base metal 15 overlaid by the precious metal be not exposed. It is also imperative that the internal chamber formed by the central enlargement of the body be everywhere sealed against any access of finishing liquids. It 20 has heretofore been customary in forming such bodies to solder together two crescent shaped shells which produced objectionable seams and openings.

The essential objects of my invention are 25 to attain the advantages and avoid the disadvantages above enumerated; to cheapen the process construction; to reduce the weight of the body to a minimum; and insure a construction adaptable for bodies of 30 small size.

The invention consists in such steps and combinations of steps, and in such parts and combinations of parts as are included within the scope of the appended claims.

35 In the accompanying drawings which form a part of this specification.

Figure 1 is a longitudinal section of the original tube from which the body is ultimately formed,

40 Figs. 2 and 3, a central longitudinal section and front view respectively of the same after the compression and elongation step,

Figs. 4 and 5, a side elevation and front view respectively of the same after the bending step,

Fig. 6, a section on line 6—6 of Fig. 4,

Fig. 7, a front view of a completed earring, and

50 Fig. 8, a longitudinal central section of the end portion of a pair of dies.

Like reference characters indicate like parts throughout the views.

In carrying out my invention a cylindrical tube 9 of metal, preferably provided 55 with a precious metal skin or plated exte-

rior surface 10, is, by the tapering dies of a reducing machine or otherwise, compressed or reduced toward its ends into conical portions 11. The reduction also elongates the member and forms solid extremities 12 due 60 to the maximum accumulation of metal at the points of greatest compression. By the described action of the dies also the plating material at the extremities is closed over completely covering the base metal, as at 13. 65

Upon an arbor or otherwise the member 9 is next bent up into crescent shape, as shown in Fig. 5.

The member is in this instance adapted for the reception of an ear wire 14 by cutting a central longitudinal slot 15 in one of the solid ends 12, to form bifurcated portions or ears 16, which are drilled to form perforations 17 to receive the pintle 18 of the ear wire. The opposite solid extremity of 75 the member 9 is nicked by any suitable tool to form a cavity 19 for the reception of the free end of the ear wire.

The reducing dies herein shown in part comprise similar upper and lower members, 80 21, provided with longitudinally disposed tapering cavities 22 terminating in rounded end portions 23.

I claim,—

1. The method of forming the ornamental body of an earring consisting in compressing and elongating an empty tube into the form of a double cone comprising solid ends, and then bending the tube into the form of an incomplete ring. 85

2. The method of forming the ornamental body of an earring consisting in elongating and tapering by compression an empty tube to form a solid metal mass at each end of the tube, next bifurcating the mass at one end, 95 perforating the bifurcated portion, and finally forming a cavity in the mass at the other end of the reduced tube.

3. The method of forming the ornamental body of an earring consisting in compressing and elongating an empty base metal tube provided with an external plating skin of precious metal until it assumes the form of a double cone comprising solid ends with the precious metal skin covering completely the 105 side and ends thereof, and then bending the tube into the form of an incomplete ring.

In testimony whereof I have affixed my signature.

CLIFFORD G. KING.
